Thos. S. Crane, Atty.

UNITED STATES PATENT OFFICE.

JOHN R. WILLIAMS, OF NEWARK, NEW JERSEY.

CIGAR-WRAPPER-CUTTING MACHINE.

SPECIFICATION forming part of Letters Patent No. 297,897, dated April 29, 1884.

Application filed August 18, 1883. (No model.)

To all whom it may concern:

Be it known that I, JOHN R. WILLIAMS, a citizen of the United States, residing in the city of Newark, county of Essex, and State 5 of New Jersey, have invented certain new and useful Improvements in Cigar-Wrapper-Cutting Machines, fully described and represented in the following specification and the accompanying drawings, forming a part of the same.

This invention consists in certain improvements in the cigar-wrapper cutter patented to me October 23, 1883, as No. 287,073, and relates to certain means for regulating and adjusting the pressure of the roller upon the cutter. 10 These improvements are shown as applied to a machine having a different means for producing the exhaust than the rotary fan heretofore shown in my said patent. With such a construction the operator is unable to use the machine unless provided with steam or other power to operate the fan, and the different construction shown herein was devised to furnish a machine in which the operator can produce the required exhaust by the use 15 of his feet and with the least possible effort. In the construction illustrated herein I have shown a machine provided with two treadles arranged to operate separately, two exhaust-bellows secured beneath the work-bench upon 20 which the cutting devices are located, and connect both the bellows with suitable check-valves to an exhaust-reservoir in which the suction is maintained uniformly. My claims in the present application are, however, restricted to the roller-adjusting devices, the 25 exhaust mechanism only being incidentally described, and the subject-matter claimed being equally applicable to machines in which no exhaust is used.

The construction will be understood by reference to the annexed drawings, in which Figure 1 is a side elevation of a machine constructed with such an exhaust apparatus, one of the bellows and the exhaust-reservoir being shown in vertical section on line xx in Fig. 4. 30 Fig. 2 is a partial front elevation of the machine, certain parts being shown in section on line yy in Fig. 1, and certain parts, as the cutter, pressing-roller, and bar t , carrying the belt-rolls w , being thus eliminated from the view, to expose the parts more fully. Fig. 3

is a plan of the work-bench and parts above it, the legs B and board X being shown in dotted lines beneath, as well as the gate-lever d and its connecting-cord c . Fig. 4 is a plan of the bellows and exhaust-reservoir, one of the bellows being shown in the act of opening, as indicated by the arrow v , and the other in the act of closing, as per arrow u , the same relative positions being indicated in Fig. 1. 55 Fig. 5 is a vertical section through the axis of the pressing-roller, a part of the arm D being also shown in section; and Fig. 6 is a transverse section of one of the pressing-rollers and its arbor. 60

A is the work-table; B , the legs for the same, to which are fastened a bar, t , and a board, X , the former carrying rolls w , over which pass belts from the treadles to the bellows, and the latter supporting the bellows and reservoir. 65

C is the cutter, provided internally with a perforated platen, C' , Fig. 3.

D is an arm, pivoted at D' and arranged to carry a pressing-roller, R , beneath its front 70 end.

E is a pipe leading from the interior of the cutter to the gate F , and G is a pipe leading from the gate to the reservoir I . 75

The valve of the gate is indicated at a , and its lever or crank at b , the latter being connected by a cord, c , to a lever, d , pivoted beneath the table or bench A within reach of the operator's knee as he sits before the bench with his feet upon the treadles H . The cord c runs over a pulley, f , and the gate-valve is constructed with a spring, (not shown,) so as to close automatically. The treadles H are hinged to a foot-board, H' , upon which the front legs, B , are placed, and belts or straps g are carried over the pulleys or rolls w from the forward ends of the treadles to the tops of the bellows, so as to expand the bellows when the treadles are depressed, and thus draw the air from the reservoir I . 80 85

The bellows consist of plates J , hinged at their lower edges to the upright board X , and of leather sides and top secured in the usual manner, and are provided with outlets e for discharging the air, and inlets e' , leading from the reservoir, both ducts being provided with suitable valves, l l' , by which the movement of 90 95

the bellows exhausts the air from the reservoir. In Fig. 1 the valve *l* is shown open and the valve *l'* closed in the bellows represented in section, while the valves or flaps are shown 5 in the opposite positions in the bellows seen in the rear. By working the bellows alternately the air may be removed with regularity from the reservoir, which consists of a rectangular chamber with collapsible leather sides to and a weight, *L*, or spring to keep it expanded. In Fig. 1 the weight *L* is represented as affixed to the movable bottom of the reservoir, which bottom is elevated by pneumatic pressure when the air within is exhausted, by the 15 bellows. When thus exhausted, the weight operates to draw air into the gate whenever the latter is opened, and the operator thus secures an instantaneous suction upon the perforated platen by pressing the gate-lever *d* at 20 his pleasure.

The bellows-plates *J* are provided with springs *J'* to close them, but may be mounted horizontally and closed by means of weights. The means I have devised for regulating the 25 pressure of the presser-roller *R* upon the edge of the cutter *C* consist in an adjustable guide-roll, *h*, secured to the arm *D* in rear of the roller *R*, and in a special construction of the 30 roller bearings and mountings. The guide-roll *h* is pivoted in the lower end of a screw-shank, *i*, which is passed through the arm *D* vertically and secured therein by jam-nuts *h'*, and a curved guide or rail, *M*, is secured upon 35 the top of the work-bench in rear of the cutter to sustain the roll *h* and arm *D* at a fixed level. The presser-roller is thus sustained at a suitable height to ride upon the edges of the cutter when the arm is swung to and fro, and may be adjusted in any desired degree by setting the jam-nuts *h'*. The roller *R* is adapted 40 to press elastically upon the cutter by means of a loose fit upon the arbor *R'*, as shown in Figs. 5 and 6, and is pressed toward the cutter by spring-rollers *m*, which are mounted in 45 sliding carriers *n*, fitted in slots *o* in the arm *D*, or in the bracket *D'*, secured to it to carry the roller, *R*. The carriers are formed with stems *s*, which project through the arm *D*, above the roller *R*, and are provided with

spiral springs *r*, which press the rollers *m* upon 50 the top of the loosely-fitted roller *R*. The latter is cut in two at the middle of its length, so that either end can revolve independently of the other, and at a rate proportioned to its distance from the fulcrum *D'*, and can also yield 55 separately to the pressure of the spring-roll above it. The roller is thus much better adapted to press and roll smoothly over the cutter, and to effectually operate on the leaf as it lies on the cutting-edges, the divided parts yielding 60 to any inequalities in the surface of the cutter, which a solid roller could not do.

It is obvious that the roller *R* may be fitted 65 differently to obtain the vertical movement and desired result.

The spring-rollers *m* may be carried and moved differently or replaced entirely by flat 65 spring-pressers.

I do not claim the combination of a roller and inverted cutter as my own invention, as 70 I am aware that the same has been secured by Letters Patent heretofore granted to R. Ap-pleby, April 8, 1873, No. 137,524; nor do I claim in the present application the subject-matter of my application No. 84,667, filed February 75 10, 1883; but

What I do claim is—

1. The combination, with the cutter *C* and arm *D*, carrying a compound presser-roller, *R*, of an adjustable guide-roll, *h*, attached to 80 the arm and fitted to a rail or guide, substantially as and for the purpose set forth.
2. The combination, with the carrying-arm *D*, of the compound presser-roller *R*, having its parts arranged to rise and fall independ- 85

3. The combination, with the arm *D* and the compound roller *R*, fitted to rise and fall, as described, of the elastic pressers applied to the upper side of the roller, substantially as 90 herein shown and described.

In testimony whereof I have hereunto set my hand in the presence of two subscribing witnesses.

JNO. R. WILLIAMS.
